UNITED STATES PATENT OFFICE.

HENRY O. JOHNSON, OF VIRGINIA, MINNESOTA.

WRENCH.

1,409,863.

Specification of Letters Patent. Patented Mar. 14, 1922.

Application filed April 4, 1921. Serial No. 458,204.

To all whom it may concern:

Be it known that I, HENRY O. JOHNSON, a citizen of the United States, residing at Virginia, in the county of St. Louis and 5 State of Minnesota, have invented certain new and useful Improvements in Wrenches, of which I do hereby declare the following to be a specification.

My invention relates to wrenches and has 10 for its object the provision of a simple, durable, convenient and effective adjustable wrench. It consists of the constructions, combinations and arrangements of parts hereinafter described and claimed.

15 In the drawings, Fig. 1 is a central vertical section partly in side elevation of my said invention. Fig. 2 is a transverse section of said invention on the line A—B, of Fig. 1.

20 In the drawings, 1 is a fixed jaw and shank, 2 is an adjustable jaw and locking tongue, 3 is a locking cam, 4 is a retracting spring, and 5 is a handle.

It will be observed that said adjustable 25 jaw is mounted upon said shank and is adapted to be reciprocated longitudinally thereof, and that said locking tongue in operative position extends parallel to said shank and is provided upon its opposing face 30 with teeth 2^a adapted to engage teeth 1^a formed upon or secured to said shank. Said locking cam is mounted on said handle and when said cam lever is drawn down to said handle, said cam is adapted to bear against 35 said tongue and to press it into locking engagement with said shank, in opposition to said spring. The spring 4, is mounted on,

or secured to either of the members 1 or 2 and is adapted to slide in a shallow groove formed in the other of said members, and is 40 adapted, when said cam is retracted, to retract the teeth of said tongue from engagement with the teeth of said shank to permit the member 2 to be reciprocated or adjusted on the member 1.

45 It is obvious that said construction may be modified or altered in various particulars within the spirit and scope of my claim.

What I claim, is—

In a wrench, the combination of a stationary terminal jaw provided with a shank, an adjustable inner jaw provided with a shank adapted to extend approximately parallel to the shank of said stationary jaw, said shanks being provided with 50 teeth in their opposing faces adapted in operation to engage each other, one of said shanks having a longitudinally extending groove formed in its toothed face, a spring positioned in said groove and adapted to extend therefrom and bear against the opposite shank, said spring being adapted to maintain a constant tendency to force said shanks apart to disengage said teeth, and means for forcing said shanks toward each 55 other to engage said teeth in opposition to said spring.

60 In testimony whereof, I hereunto affix my signature in presence of two witnesses.

HENRY O. JOHNSON.
